(57) **CLAIM**

The ornamental design for bone shaped linkage for animal products, as shown and described.

DESCRIPTION

FIG. 1 is a perspective view of a bone shaped linkage for animal products, according to the present invention;

FIG. 2 is a side view of the bone shaped linkage for animal products, according to the present invention;

FIG. 3 is a end view of the bone shaped linkage for animal products, according to the present invention;

FIG. 4 is a second side view of the bone shaped linkage for animal products, according to the present invention;

FIG. 5 is a second end view of the bone shaped linkage for animal products, according to the present invention;

FIG. 6 is a third side view of the bone shaped linkage for animal products, according to the present invention; and,

FIG. 7 is a view of the bone shaped linkage for animal products, according to the present invention, illustrating an open position.
